UNITED STATES PATENT OFFICE

WILHELM EDUARD ERICH HABANN, OF BERLIN, GERMANY

METHOD FOR TRANSMITTING THE SPEECH BY HIGH-FREQUENCY WAVES

Application filed September 17, 1924, Serial No. 738,297, and in Germany October 2, 1923.

In the employment of interrupters according to the specification of United States Patent No. 1,569,481 or similar transmitters for transmitting speech by the aid of electric waves, in which the speech is resolved solely by mechanical high frequency interruption, or ohmic, or inductive, or capacity-resistance changes into high frequency impulses, and thus converted into modulated high frequency currents, the difficulty is experienced that if a receiver such as the usual audion receiver, for instance, is used, there is distortion of the speech. This distortion occurs, because, while single sounds can be heard fairly distinctly in the audion receiver, the clearness decreases when speech of a plurality of sounds is to be transmitted. This drawback, it is true, can be overcome in a known manner, if a minor continuous current be added to, or compounded with, the low frequency speaking current. The use of this continuous current, however, is inconvenient in that it causes continuous, though weak, electric vibrations, which must be avoided for reliable multiplex conversation.

For a long time the causes of such speech distortion were sought in the mechanical high frequency interrupter itself, and proposals for improvement were directed to constructive alterations in the interrupter, until it was found, with surprise, that the high frequency interrupter itself was not the source of the trouble. It was then found that when working, for instance, with high frequency interrupter according to the said specification Patent Number 1,569,481, together with a receiver constructed similarly to the transmitter, all difficulties were removed. It was also found that the frequency interrupter was capable of working reversibly, in that it not only converts, on the transmitter side, low frequency speech into sound-damped high frequency currents, but also converts sound-damped high-frequency currents into low frequency speech. The electric connection on the receiver side is identical with the known electric connection on the transmitter side. In order then to obtain full clearness of speech in using a transmitter and a receiver analogous to one another it is merely

necessary that both devices should have mechanical frequencies in strict harmonic relation, that is to say, the ratio of the frequencies of the interrupters shall be unity or a fraction whose denominator shall always be a whole number. It is not essential however that the frequencies of the interrupters shall be synchronously in phase, in other words, the mechanical breaks need not occur simultaneously.

Now by the invention it is possible to transmit speech undistorted and perfectly distinctly without the addition of, or compounding with, continuous currents on the transmitter side which would prejudice multiplex conversation, and therefore without any continuous or undamped high frequency current on either the transmitter side or the receiver side. A rectifier on the receiver side is not necessary.

In the drawing the sole figure represents diagrammatically a system for transmitting speech by electric waves shown by way of example for carrying out the invention.

The speaking currents from the subscriber's station A which includes a microphone *a* and a telephone *b*, are conducted by the transformer *T* on both sides of the condenser *k* to the circuit *c*, in which by the plugs 10 and 11 is included a mechanical interrupter of any kind (not shown) for instance such as is described in applicant's former Patent No. 1,569,481. By these means the speaking currents are divided up and conducted to the oscillatory circuit *S*₁ which is coupled with the long-distance line *F* which at its other end is coupled with a similar system of another subscriber's station B. The latter may be considered the receiver if station A is used as sender.

It is indispensable that the sending oscillatory circuit *S*₁ and the receiving oscillatory circuit *S*₂ are tuned to the same frequency. The frequencies of the interrupters may be either the same as the frequency of the said oscillatory circuits or the frequency of said circuits divided by 1, 2, 3, or any other integer.

It is not essential that this integer be the same for the two interrupters, consequently,

the ratio of the interrupter frequencies may have such values as 1:2; 4:5; 3:2; 6:1, etc., the ratio 1:1 being excluded.

By the invention multiplex conversation absolutely free of interference with distinct speaking, is rendered possible, because the presence is avoided of any undamped transmitter which would cause disturbances by interferences owing to the spatial or unipolar 10 relationship to the rest of the highly sensitive parts of the apparatus.

Having now particularly described and ascertained the nature of my said invention and in what manner the same is to be performed, I 15 declare that what I claim is:—

In the transmission of speech by electric waves in which low frequency speech currents are resolved into impulses by the aid of mechanical interrupters in which a similar 20 arrangement is operative on the receiving side as on the sending side, whereby both the sending device and the receiving device are connected with the main line over electric resonance circuits, tuned to the same frequency, the method which comprises operating 25 the sender and the corresponding receiver with mechanical transmission frequencies which are in exact harmonic relation other than a one to one relation with one another.

WILHELM EDUARD ERICH HABANN.
